UNITED STATES PATENT OFFICE.

AUGUSTIN H. GOELET, OF NEW YORK, N. Y.

DESIGN FOR A SPECULUM.

SPECIFICATION forming part of Design No. 19,398, dated November 5, 1889.

Application filed August 5, 1889. Serial No. 319,835. Term of patent 14 years.

To all whom it may concern:

Be it known that I, AUGUSTIN H. GOELET, of New York city, in the county and State of New York, have invented and produced a new and original Design for a Speculum, of which the following is a specification, reference being had to the accompanying drawing, forming a part thereof.

The leading feature of the design consists in a central shank having parallel trough-shaped members projecting in opposite directions.

A represents the central shank, of rounding contour, from the ends of which are projected

the trough-shaped members B B on parallel lines and in opposite directions. The concave sides of the members face oppositely to each other, and the inner open ends merge or vanish on rounding lines into the shank. The outer ends of the members present a rounding appearance.

I claim—

A design for a speculum, substantially as shown and described.

AUGUSTIN H. GOELET.
